Gaetano Salvatore Buccino, Bethel, and Jack Marks Granowitz, Danbury, Conn., assignors to American Cyanamid Company, Stamford, Conn., a corporation of Maine

Continuation of design applications Ser. No. 3,129, July 19, 1966, and Ser. No. 3,135, July 19, 1966. This application Oct. 13, 1967, Ser. No. 8,993

Term of patent 14 years

U.S. Cl. D33—19

Int. Cl. D6—01

FIGURE 1 is a front perspective view of a locking stackable suture box cabinet showing our new design; FIGURE 2 is a fragmentary view taken along the lines 2-2 of FIGURE 1;

FIGURE 3 is a modified form of the cabinet of FIGURE 1; and

FIGURE 4 is a sectional view taken along the lines 4-4 of FIGURE 4.

The back of the cabinet is plain and unornamented.

This application is a continuation of our two earlier filed applications Ser. Nos. D.3,129 and D.3,135 filed July 19, 1966 and now abandoned.

We claim:

The ornamental design of a locking stackable suture box cabinet, as shown and described.
